Primary Examiner — Ricky Pham*(74) Attorney, Agent, or Firm* — Franklin & Associates International Inc; Matthew F. Lambrinos(57) **CLAIM**

The ornamental design for a top part of a knife eating utensil, as shown and described.

DESCRIPTION

FIG. 1 is a left side bottom perspective view of a top part of a knife eating utensil showing my new design;

FIG. 2 is a first end view thereof;

FIG. 3 is a left side elevation view thereof;

FIG. 4 is a right side elevation view thereof;

FIG. 5 is a second end view thereof;

FIG. 6 is a top plan view thereof;

FIG. 7 is a bottom plan view thereof; and,

FIG. 8 is a top, and left side perspective view thereof.

The handle of the knife eating utensil is shown in broken lines for illustrative purposes only and forms no part of the claimed design.

1 Claim, 8 Drawing Sheets(56)
